UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

UNCOUPLING DEVICE FOR CAR COUPLERS.

Application filed June 4, 1923. Serial No. 643,266.

This particular invention relates to what is generally known in the art as the push down or vertical plane type of uncoupling device for car couplers and comprises two levers having their adjacent ends pivotally mounted on the same fulcrum. Such devices are operated either by the hand or foot. (The particular advantage of this construction resides in the manner in which the levers are pivoted upon the fulcrum.) In levers of this general type the connection between the levers must allow the pin lifting lever to move freely laterally to accommodate the longitudinal movement of the coupler in draft and in buffing.

The manner of operatively connecting the two levers and mounting them on a common fulcrum, in accordance with this invention, provides a separate connection allowing play of the fulcrum end of the pin lifting lever in a horizontal plane without transmitting such movement to the operating lever, and furthermore, provides means of operatively attaching the operating lever to the fulcrum which prevents or restricts its lateral movement.

The impact of coupling causes sudden longitudinal movement of the coupler, which movement is transmitted to the adjacent end of the pin lifting lever and would be transmitted to the operating lever unless that lever is prevented from moving laterally. Switchmen frequently ride a moving car while coupling it and at the same time signal the engineer. In such an act he usually holds on to the grab iron with his left hand and signals the engineer with his right hand while his left foot is on the sill step and his right foot is on the operating lever. While in such a position a sudden movement of the operating lever has a tendency to, and frequently does, throw him from the car. One of the objects, therefore, is to provide a device which is safe for the switchman to operate.

A separate connecting member and bearing block has the advantages of increasing the bearing area on the journal fulcrum thereby reducing the friction and making the device easier to operate and also reducing the wear on the associated parts. The connecting block non-rotatively connects the operating lever and the pin lifting lever so that a force exerted on the outer end of

the operating lever raises the inner end of the pin lifting lever.

The connection between the levers surrounds the fulcrum and tilting of the operating lever from the vertical plane is prevented by positioning the operating lever between a shoulder on the fulcrum member and shoulders or shoulder on the connecting block and the pin lifting lever is prevented from tilting by being positioned between the operating lever and a projection on the connecting block. This elimination of the tilting of the levers considerably reduces the friction between the levers and their fulcrum.

Good practice requires that the handle end of the operating lever be positioned slightly in front of the vertical plane of the face of the end sill and below the push pole pocket. This is a generally recognized location of this handle; therefore, switchmen can reach it quickly even in the darkness. It is advantageous, therefore, to not permit the lever to move laterally, and especially advantageous not to allow the sudden or jerky movement of the pin lifting lever to be transmitted to the operating lever.

Another object is to provide an arrangement for connecting the two levers to the fulcrum which also prevents the levers from tipping and thereby binding on the fulcrum and causing friction.

Means are provided to restrict the movement of the lever in a vertical plane which is a requirement of the Interstate Commerce Commission safety appliance acts.

In the drawings:

Fig. 1 is a fragmentary front view of a freight car with the device applied thereon.

Fig. 2 is a perspective view of the fulcrum casting.

Fig. 3 is a perspective view of the connecting and bearing block.

Fig. 4 is a perspective view of the washer.

Fig. 5 is a perspective view of the nut.

Fig. 6 is a plan view showing the connection of the levers with the parts in operative assembled position.

Fig. 7 is a perspective view of the fulcrum end of the operating lever.

Fig. 8 is a perspective view of the fulcrum end of the pin lifting lever.

The end sill 1; push pole pocket 2; striking casting 3, and coupler 4 are usual parts

2
of the car. The fulcrum casting 5 is secured to the end sill or other part of the car by rivets 6 and the fulcrum has an integral journal 7 upon which is rotatively mounted the connecting and bearing block 8. This bearing block is held in operative position by washer 9 which in turn is held in place by bolt 10 and nut 11.

The exterior perimeter of the connecting block 8 is rectangular and the operating lever 12 and pin lifting lever 13 are provided with rectangular apertures 14 and 15 respectively through which the connecting block 8 passes so as to provide a non-rotative connection between the levers and the connecting block. While the drawings illustrate rectangular apertures it is understood that any arrangement which provides a non-rotative connection between the levers and the connecting block will come within the scope of this invention.

That portion 16 of the connecting block which engages the operating lever 12 is slightly smaller than the portion 17 which engages the pin lifting lever 13 thereby forming shoulders 18 which shoulders together with the shoulders 19 provided by the fulcrum casting, form means for restricting the lateral movement of the operating lever, that is, when the device is in assembled operative position. The fulcrum end of the pin lifting lever is deflected, as shown in Fig. 8, and positioned between the operating lever and pointed shoulder 20 on the connecting block so that it is free to move laterally to accommodate the draft movements of the coupler but does not transmit such movement to the operating lever. Furthermore, the positioning of the fulcrum end of the operating lever between the adjacent shoulders prevents or substantially restricts the operating lever from moving laterally.

The pin lifting lever 13 is connected to the eye 21 of the coupler lock lifter in the usual manner and the operating lever 12 is extended toward the outer wall of the car so that the handle 22 or pedal 22 is located in any desired position.

While this invention is illustrated as applied to a certain type of freight car, it is readily adapted with but slight immaterial changes for application to other types.

I claim:

55. 1. In an uncoupling device for railway cars comprising an operating lever having an aperture adjacent its fulcrum end, a pin lifting lever having an aperture adjacent its fulcrum end, a member passing through said apertures having non-rotative connection therewith, a fulcrum passing through said member having a rotative connection therewith, and means integral with said parts restricting lateral movement of said operating lever.
60. 2. In an uncoupling device for railway

cars comprising an operating lever having an aperture adjacent its fulcrum end, a pin lifting lever having an aperture adjacent its fulcrum end, a double shouldered member passing through said apertures having a non-rotative connection therewith, a shouldered fulcrum passing through said member having a rotative connection therewith, said operating lever positioned between the shoulder on the fulcrum and one of the shoulders on said member, and said pin lifting lever positioned between the shoulders on said member.

3. In an uncoupling device for railway cars comprising an operating lever having an aperture adjacent its fulcrum end, a pin lifting lever having an aperture adjacent its fulcrum end, a shouldered member passing through said apertures having a non-rotative connection therewith, a shouldered fulcrum passing through said member having a rotative connection therewith, said operating lever positioned between the shoulder on the member and the shoulder of the fulcrum so as to restrict its lateral movement, and means to retain said parts in operative position.

4. In an uncoupling device for railway cars comprising an operating lever having an aperture adjacent its fulcrum end, a pin lifting lever having an aperture adjacent its fulcrum end, a two shouldered member passing through said apertures having a non-rotative connection therewith, a shouldered fulcrum passing through said member having a rotative connection therewith, said operating lever positioned between the shoulder on the fulcrum and one of the shoulders on said member so as to restrict its lateral movement, said pin lifting lever positioned between the other shoulder on said member and the operating lever so as to permit sufficient lateral movement to accommodate the device in service, and means to retain said parts in operative position.

5. In an uncoupling device for railway cars comprising an operating lever having an aperture adjacent its fulcrum end, a pin lifting lever having an aperture adjacent its fulcrum end, a two shouldered member passing through said apertures having a non-rotative connection therewith, a shouldered fulcrum passing through said member having a rotative connection therewith, said operating lever positioned between the shoulder of the fulcrum and one of the shoulders on said member so as to restrict its lateral movement, said pin lifting lever having its fulcrum end deflected and positioned between the other shoulder on said member and the operating lever so as to permit sufficient lateral movement to accommodate the device in service, and means to retain said parts in operative position.

6. In an uncoupling device for railway

- cars comprising an operating lever having an aperture adjacent its fulcrum end, a pin lifting lever having a larger aperture adjacent its fulcrum end, a member having an exterior portion which passes through and non-rotatively engages the aperture of the operating lever and having another larger exterior portion which passes through and non-rotatively engages the apertures of the pin lifting lever, a fulcrum passing through said member having a rotative connection therewith, and means to retain said parts in operative position.
7. As an article of manufacture for uncoupling devices for car couplers; a combined connecting member and bearing block having a circular interior bearing and two polygonal exterior lever engaging portions of different sizes forming a shoulder.
8. As an article of manufacture for uncoupling devices for car couplers; a combined connecting member and bearing block having a circular interior bearing and two polygonal exterior lever engaging portions of different sizes forming a shoulder; a pin lifting lever having a larger aperture adjacent its fulcrum end, one of said apertures being larger than the other, a member having separate exterior portions which pass through and non-rotatively engage said apertures, a fulcrum passing through said member having a rotative connection therewith, and means to retain said parts in operative position.

9. In an uncoupling device for railway

10 cars comprising an operating lever having an aperture adjacent its fulcrum end, a pin lifting lever having an aperture adjacent its fulcrum end, one of said apertures being larger than the other, a member having sep- 15 arate exterior portions which pass through and non-rotatively engage said apertures, a fulcrum passing through said member hav- 20 ing a rotative connection therewith, and means to retain said parts in operative posi- 25 tion.

GARTH G. GILPIN.
